FOREIGN PATENT DOCUMENTS

TW D155582 8/2013

Primary Examiner — Elizabeth J Oswecki*(74) Attorney, Agent, or Firm* — Lowenstein Sandler LLP(57) **CLAIM**

The ornamental design for a mainframe with integrated lid, as shown and described.

DESCRIPTION

FIG. 1 is a top, front perspective view of a mainframe with integrated lid showing our new design;

FIG. 2 is a side view thereof;

FIG. 3 is an opposite side view thereof;

FIG. 4 is a front view thereof;

FIG. 5 is a rear view thereof;

FIG. 6 is a top view thereof;

FIG. 7 is a bottom view thereof; and,

FIG. 8 is another top, front perspective view thereof, shown in a used condition with unclaimed components attached. The broken lines shown in the figures are directed to unclaimed portions of the mainframe in FIGS. 1-8 and unclaimed components attached to the mainframe in FIG. 8 that form no part of the claimed design.
